Specification of Letters Patent.

Patented July 2, 1912.

Application filed September 26, 1911. Serial No. 651,338.

To all whom it may concern:

Be it known that I, HIRAM P. HALL, a citizen of the United States, residing at New York city, county of New York, and State of New York, have invented a new and useful Improvement in Cartridge-Loading Machines, of which the following is a full, clear, and exact description, reference being had to the accompanying drawings, which form a part of this specification.

The object of my invention, in general, is to provide a power machine for filling and packing paper shells with dynamite or other explosive. Such a machine is set forth in the patent issued to me March 22, 1898, No. 601,138.

The more particular object of my invention is to improve the construction and operation of the machine of said patent and of later machines of the same general character.

I will first describe the construction and operation of my improved machine and will then particularly point out the more notable of the advantageous features thereof.

In the drawings: Figure 1 is a sectional elevation of the machine. Fig. 2 is a plan view of the upper portion of the machine. Fig. 3 is an elevation of the portion of the machine shown in Fig. 2. Fig. 4 and Fig. 5 are detail sectional views of the lower portion of the machine.

The ceiling 101 divides the machine into two parts. One part, comprising the shell-holder, hopper, feed-chute, and a part of the tamp-guiding mechanism, is located on the lower floor. The upper floor contains the actuating mechanism for the vertically reciprocating tamps, the latter extending from one floor to the other, as in my said patent.

My improvement relates mainly to the actuating mechanism for the tamp rods; and certain parts of the machine, such as the means for feeding the dynamite to the hopper, the means for opening and closing the shell holders, and the means for crimping and folding the shells, are not shown, as they form no part of my present invention.

Referring first to Fig. 1: 10 is a revoluble shell-holder similar in operation to the one set forth in my said patent. The shell holder carries the shells 11 to be loaded. Above the shell holder is the hopper 12

adapted to contain the dynamite to be packed into the shells. Above the hopper 12 is the feed-chute 13.

14, 14, etc., represent the plungers or tamp rods, which reciprocate vertically within the hopper 12 and pack the dynamite in the shells 11. The tamp rods 14 are guided near their upper ends in the guides 15. Secured to each tamp rod 14 is a collar 16, connected, by means of a connecting rod 17, with the end of a steel tube 18 rigidly fastened on the end of an arm 19 projecting from an eccentric strap 20. Each rod 14, and its corresponding collar 16, rod 17, tube 18, arm 19 and strap 20, constitute an independent tamping device. Each eccentric strap 20 surrounds semi-circular wedges 21 and 22, the former being pinned fast to the strap and the latter not being connected to the strap except frictionally as hereinafter described. Each pair of wedges 21 and 22 surround, or to be more accurate, nearly surround, the drum or cylinder 23, which is slightly longer than the width of the space occupied by all the tamp rods, straps 20 and wedges. The cylinder 23 is mounted on and secured to the shaft 24, which extends completely across the machine and turns in bearings on the machine frame 100. Each movable wedge 22 is normally held tightly in place between the corresponding strap 20 and the cylinder 23 by means of a block 25 secured to wedge 22 and pressed in the direction of the single arrow by means of a spring 26 confined between block 25 and a lug 27 on the strap 20. By means of adjusting screws 28, the tension of the springs 26 may be regulated. By means of the adjustable plates 29, the wear on the movable wedge 22 is taken up.

The shaft 24 is continuously oscillated by the following means. 30 is the main driving shaft turning in bearings on the machine frame. At each side of the machine the shaft 30 is provided with a spur-gear 31, which meshes with a spur gear 32 on a shaft 33. On the latter shaft is a crank 34, which, by means of a crank-pin 35 and a connecting rod 36, is connected with a crank pin 37 on the crank 38 secured to the shaft 24.

40 is a double-acting cylinder having a compressed air inlet and outlet at 41 and 42.

43, 43, are stationary arms secured to the frame of the machine at opposite sides there-

of and having bearings for the shaft 44, which extends completely across the machine. To the shaft 44 is keyed, at one side of the machine, the bell-crank lever 45. One arm of the bell-crank 45 is connected to the piston rod 46 of the cylinder 40. The other arm of the bell-crank 45 supports the shaft 47 which extends completely across the machine. On the other side of the machine, a simple lever 48 is keyed to the shaft 44 and supports the shaft 47. Pivoted on the shaft 47 are levers 50, one for each tamp. The outer ends of levers 50 are slotted to receive a rod 49 which extends completely across the machine and is supported by arms 490 on opposite sides of the machine. On each lever 50 is a lug 51 adapted to engage a lug 52 on the corresponding eccentric strap 20. On each lever 50 is a lug 53 adapted to engage a dogging lever 54 fulcrumed on the strap 20 and fitting into a recess 55 in the movable wedge 22.

To make the machine extremely sensitive lead weights 59 are placed on each eccentric strap 20 opposite the steel tube 18. They can be made to nearly balance the tamp rods 14.

In the drawings, Fig. 1, the machine is shown as at rest and with all the tamps dogged. The cylinder 23 is oscillating as described. The weight of the tamp-rods 14 causes the upper ends of the levers 54 to bear against the vertical sides of the lugs 53, thereby causing the wedges 22 to be moved in the direction of the double arrow and out of driving engagement with the cylinder 23 and strap 20. The cylinder 23 is therefore ineffective to vibrate the strap 20.

In starting the machine air is admitted into the cylinder 40 through port 41. This imparts motion to the cam levers 50. The lugs 51 on levers 50 engage the lugs 52 on the eccentric straps 20 and cause the latter to turn, thereby depressing the various tamp rods 14 until they pass through the hopper and punch the first particles of powder into the shells. It should be noted that this first down-stroke of the tamping rods is a positive one, thereby insuring that the lower ends of the shells shall be packed with a certain degree of tightness and thus avoiding softness in the lower ends of the shells. As the cam-levers 50 ride on the rod 49, the lugs 53 are disengaged from the dogging levers 54 during the first stroke of the machine. As soon as the air is released from the cylinder 40, the opposing air at once returns the cam levers 50 to their initial positions. As soon as the cylinder 40 has completed the first stroke the oscillating cylinder 23 reverses its motion from the direction of the double arrows to the direction of the single arrow. At once the movable wedges 22 jam and cause the straps 20 to turn with the cylinder 23, thus lifting the tamping

rods 14 a definite distance to the upper ends of their strokes. As soon as the cylinder 23 again reverses its motion and turns in the direction of the double arrows, the straps 20 also reverse their motions and a downward movement is imparted to the tamping rods 14. As soon as the tamping rods 14 pass through the hopper and compress an additional amount of powder into the shells with a predetermined degree of tightness, the resistance to further downward movement of the tamping rods arrests them and also their respective straps 20, which slip relatively to the cylinder 23.

The tension of the springs is slightly greater than the weight of the tamps, thereby preventing the weight of the tamps from opening up the wedge, said springs serving therefore, to hold the cylinder 23 and straps 20 in driving engagement during the down stroke of the tamps until their tension is overcome by the opposing resistance of the packed powder. The amount of compression that is given to the powder in the shells is thus determined by the difference between the weight of the tamps and the tension of their respective springs 26. The amount of compression can be varied by varying the tension of the springs 26 by means of the adjusting screws 28. The composite drum continues to oscillate and the eccentric straps 20 forming part thereof continue to slip to an extent proportionate to the amount of powder packed into the respective shells at each down-stroke of the tamp-rods. As soon as any shell is completely filled, the corresponding dogging lever 54, which has engaged the corresponding lug 53 and thus lifted the corresponding lever 50, slips back of said lug 53, and the lever 50 dropping, this particular dogging lever 54 is dogged. At once the point of lug 53 contacting with the lever 54 becomes the fulcrum of that lever, and the power (the weight of the corresponding tamp rod 14) acts to move the corresponding wedge 22 out of driving engagement with the cylinder 23. Immediately the corresponding strap 20, and likewise the corresponding tamping rod 14, are brought to rest. Thereafter in the oscillation of cylinder 23, no work is done upon this particular tamping rod. As soon as all the tamps are dogged in a similar manner, the machine is again brought to rest, and the shell cylinder 10 is turned to bring a new set of shells into position to be filled.

Instead of providing stirrers in the hopper, the tamping rods themselves are given a vibratory movement coincident with their up and down movement, thereby avoiding the possible danger that arises from the employment of independent mechanism for stirring. The actuating mechanism for imparting this vibratory motion to the stirrers will now be described.

The driving shaft 30 has keyed to it, on each side of the machine, a spur gear 60, which drives a spur gear 61, loose on the shaft 33. On the hub of gear 61 is a projecting arm 62 which engages alternately the inwardly projecting parts 63 and 64 of a cam 65. This cam encircles the arm 62 and is carried on one arm of a bell-crank lever 66 pivoted on a pin 67 turning in bearings 10 on the machine frame. The other arm of the bell-crank 66 carries a slotted bar 68, which extends entirely across the machine. This slotted bar is wide enough to allow the tamping rods 14 to slide easily therethrough.

The alternate engagement of cam projections 63 and 64 by the rotating arm 62 vibrates the bell-crank 66 and therefore vibrates the tamping rods 14. The ratio of the gearing is such that the tamping rods 14 are given a complete reciprocation down and up when they are moved to one side of the hopper and another complete reciprocation when they are moved to the other side of the hopper.

Each tamp-rod 14 is equipped with a guide piece 70 the opposite ends of which carry fiber or other suitable material. On the downward stroke of the tamp rod, the guide piece 70 contacts with one of the metallic guides 71 fastened to the frames 72 extending beneath the ceiling 101. These guides correspond in shape with the shape of the hopper, the object being to carry the rubber-tipped end of the tamp-rod down along the side of the hopper but not quite touching it.

By means of above devices, the lower ends of the tamp rods are caused to move down through the powder obliquely and close to the slanting walls of the hopper, first on one side and then on the other, thereby preventing the formation of any open pockets in the powder and preventing the accumulation of powder along the side walls of the hopper.

To prevent the tamps from moving from the position to which they are brought at each movement of the bell-crank levers 66, lead weights 69 are placed directly over the fulcrum of said bell-cranks. These weights hold the bell cranks and tamp-rods on that side of the perpendicular to which they have been moved by the engagement of arms 62 with either of the cam projections 63 or 64.

To prevent with absolute certainty the escape of any dust upwardly onto the guides 71 and frame 72, a plate of hard rubber or fiber 78 is fastened to each tamp rod 14, said plate sliding over a plate 74 secured to and connecting the lower ends of the frames 72 and extending across the machine, plate 74 being provided with a slot wide enough to permit the tamp rods to vibrate back and forth. Each plate 78 is of a width equal to the distance from center to center of adjacent tamps, so that the plates of ad-

jacent tamps touch each other. Thus the opening in plate 74 is constantly sealed and no dust can rise to the level of the guides 71.

The lower end of the hopper 12 is provided with individual funnels 80, one for each tamp-rod. These funnels are formed in a frame 81, which extends entirely across the machine and is provided with side flanges 82 bolted to side flanges 83 on the hopper 12. Beneath the funnels 89 are nipples 84 suspended from a plate 85 extending across the machine. This plate is bolted to flanges 86 on the funnel-frame 81, the flanges 86 extending downward beneath the plate 85 at one side and at both ends of the machine.

The main advantages of a machine embodying the features hereinbefore described may be enumerated as follows: 1. Capacity for proper oiling of the tamps, which is impracticable where the frictional driving mechanism directly engages the tamp rods. 2. Strong frictional grip upon the tamps by means of the tapering wedges, thereby giving greater lifting power to the tamps than heretofore, and actuating them more positively on the up stroke than the down stroke. 3. A positive stroke of definite distance on the initial down-stroke of the tamps, which has been referred to hereinbefore. 4. Economy of power in driving the machine, as it is clear that the rocking drum can be actuated with less power than a reciprocating bar directly engaging the tamp rods. 5. Elimination of the stirrers in the hopper, their function being performed with equal efficacy and more safety by the vibratory movement imparted to the tamping rods. 6. Absolute control of the density with which the powder is packed into the shells by the adjustment of the springs 26, thereby enabling the packing of cartridges of any weight and of uniform weight. 7. The provision of individual funnels for each tamp, and the arrangement whereby quick changes can be made from one size of nipple to another, thereby enabling shells of different sizes to be punched without substantial delay in changing from one size to another. 8. The provision of means to prevent dust from rising from the hopper to the mechanism above the same.

Having now fully described my invention, what I claim and desire to protect by Letters Patent is:

1. In a machine for filling shells the combination with a series of independent tamping rods, of driving mechanism to reciprocate said rods and permit them to independently feed progressively backward as the shells become filled, said means dictating a positive movement of the rods for a determinate distance on their initial packing stroke.
2. In a machine for filling shells, the com-

- 6 combination with a series of independent tamping devices, driving mechanism frictionally engaging the tamping devices to reciprocate them and permit them to independently feed progressively backward as the shells become filled, and driving means positively engaging the tamping devices and adapted to move them forward on their initial packing stroke.
- 10 8. In a machine for filling shells, the combination with a series of independent tamping devices, driving mechanism frictionally engaging the tamping devices to reciprocate them and permit them to independently feed progressively backward as the shells become filled, driving means adapted to positively engage the tamping devices and move them forward independently of the frictional driving mechanism, and means to render the positive driving means inoperative and permit the tamping devices to be actuated solely by the frictional driving mechanism.
- 14 9. In a machine for filling shells, the combination with a series of independent tamping devices, of a reciprocating driving member, a movable wedge interposed between the driving member and each tamping device, and a spring interposed between each tamping device and the wedge tending to seat said wedge to enable the driving member to actuate the tamping device but permitting the wedge to unseat upon a predetermined resistance to movement of the tamping device.
- 18 10. In a machine for filling shells, the combination with a series of independent tamping devices, of a reciprocating driving member, a movable wedge interposed between the driving member and each tamping device whereby the latter is reciprocated, a dogging lever carried by each tamping device and engaging said wedge, and means adapted, upon a predetermined retraction of the tamping device relatively to the driving member, to engage said lever and actuate it to unseat said wedge and thereby stop the operation of the tamping device.
- 22 11. In a machine for filling shells, the combination with a series of independent tamping rods, of a driving cylinder, means to oscillate the same, wedges, one for each tamping rod, engaging the driving cylinder, eccentric straps one for each wedge, and means connecting the several straps with their respective tamping rods.
- 26 12. In a machine for filling shells, the combination with a series of independent tamping rods, of a driving cylinder, means to oscillate the same, wedges, one for each tamping rod, engaging the driving cylinder, eccentric straps one for each wedge, a spring, interposed between each strap and its corresponding wedge, tending to seat said wedge between the cylinder and the strap, and means connecting the several straps with their respective tamping rods.
- 30 13. In a machine for filling shells, the combination with a series of independent tamping rods, of a driving cylinder, means to oscillate the same, straps, one for each rod, eccentrically surrounding the driving cylinder, means connecting the straps with their respective rods, a wedge extending part way around the driving cylinder and interposed between it and the straps and fixedly secured to the latter, and movable wedges, one for each strap, extending part way around the driving cylinder and interposed between it and the straps.
- 34 14. In a machine for filling shells, the combination with a series of independent tamping rods, of a driving cylinder, means to oscillate the same, straps, one for each rod, eccentrically surrounding the driving cylinder, means connecting the straps with their respective rods, a wedge extending part way around the driving cylinder and interposed between it and the straps and fixedly secured to the latter, movable wedges, one for each strap, extending part way around the driving cylinder and interposed between it and the straps, and springs, one interposed between each wedge and its corresponding strap, tending to seat said movable wedges but permitting the movable wedge to unseat upon predetermined resistance to movement of the tamping rods.
- 38 15. In a machine for filling shells, the combination with a series of independent tamping rods, of a driving cylinder, straps eccentrically surrounding the driving cylinder and connected with the respective tamping rods, wedges interposed between the respective tamps and the driving cylinder, means to oscillate the cylinder thereby oscillating the straps when the wedges are seated, and independent means to positively turn the straps in the direction to depress the tamping rods.
- 42 16. In a machine for filling shells, the combination with a series of independent tamping rods, of a driving cylinder, straps eccentrically surrounding the driving cylinder and connected with the respective tamping rods, wedges interposed between the respective tamps and the driving cylinder, means to oscillate the cylinder thereby oscillating the straps when the wedges are seated, a dogging lever fulcrumed on each strap and engaging said wedge, and means adapted, upon a predetermined retraction of a strap relatively to the cylinder, to engage the corresponding lever and actuate it to unseat the corresponding wedge and thereby stop the reciprocation of the corresponding tamping rod.
- 46 17. In a machine for filling shells, the combination with a series of independent

- tamping rods, of a driving cylinder, straps eccentrically surrounding the driving cylinder and connected with the respective tamping rods, wedges interposed between the respective tamps and the driving cylinder, means to oscillate the cylinder thereby oscillating the straps when the wedges are seated, a spring interposed between each strap and its corresponding wedge tending to seat said wedge to enable the driving cylinder to actuate the strap but permitting the wedge to unseat and the strap to retract relatively to the driving cylinder upon a determinate resistance to movement of the 10 tamping device, a dogging lever fulcrumed on each strap and engaging the corresponding wedge, and means adapted upon a predetermined retraction of a strap relatively to the cylinder, to engage the corresponding lever and actuate it to hold the corresponding wedge unseated and thereby stop the reciprocation of the corresponding tamping rod.
13. In a machine for filling shells, the combination with a series of independent tamping rods, of a driving cylinder, straps eccentrically surrounding the driving cylinder and connected with the respective tamping rods, wedges interposed between the respective tamps and the driving cylinder, means to oscillate the cylinder thereby oscillating the straps when the wedges are seated, sliding levers adjacent to the straps, means to slide the levers, and means 25 on the levers adapted to engage the straps and turn them positively.
14. In a machine for filling shells, the combination with a series of independent tamping rods, of a driving cylinder, straps eccentrically surrounding the driving cylinder and connected with the respective tamping rods, wedges interposed between the respective tamps and the driving cylinder, means to oscillate the cylinder thereby oscillating the straps when the wedges are seated, swinging levers adjacent to the straps, dogging levers fulcrumed on the straps and engaging the wedges, and a projection on each swinging lever adapted to 30 override the corresponding dogging lever when its corresponding strap has been retracted to a predetermined extent, and abut against said dogging lever and thereby unseat the corresponding wedge during the following forward oscillation of the driving cylinder.
15. In a machine for filling shells, the combination with a series of independent tamping rods, of a driving cylinder, straps eccentrically surrounding the driving cylinder and connected with the respective tamping rods, wedges interposed between the respective tamps and the driving cylinder, means to oscillate the cylinder thereby oscillating the straps when the wedges are seated, a spring interposed between each strap and its corresponding wedge tending to seat said wedge to enable the driving cylinder to actuate the strap but permitting the wedge to unseat and the strap to retract relatively to the driving cylinder upon a determinate resistance to movement of the 10 tamping device, a dogging lever fulcrumed on the straps, and engaging the wedges, and a projection on each lever adapted to override the corresponding dogging lever when its corresponding strap has been retracted to a predetermined extent and abut against 15 said dogging lever and thereby unseat the corresponding wedge during the following forward oscillation of the driving cylinder.
16. In a machine for filling shells, the combination with a series of independent tamping rods, of a series of oscillating members connected to said rods, and oscillating driving mechanism frictionally engaging said members and adapted to permit each member to progressively retract relatively to its driving mechanism as the shells become filled.
17. In a machine for filling shells with explosive powder, a series of tamping rods, a hopper through which said rods reciprocate, and means to reciprocate said rods longitudinally and also oscillate them back and forth within the hopper, whereby the powder is stirred by the tamping rods themselves.
18. In a machine for filling shells, the combination with a hopper, of a series of tamping rods, means to reciprocate said rods longitudinally, means to swing said rods sidewise, and means, engaging said rods in their longitudinal movement, adapted to cause the tamping ends of said rods to move transversely within the hopper.
19. In a machine for filling shells the combination with a shell-holder and a hopper, of a series of tamping rods, means to swing the rods back and forth and to reciprocate them toward and from the shell holder, guide pieces carried by the tamping rods, and guides along which said guide pieces slide during longitudinal movement of the rods, whereby the tamping ends of the rods will move through the hopper obliquely toward the shell holder.
20. In a machine for filling shells the combination with a shell-holder and a hopper, of a series of tamping rods, means to swing the rods back and forth and to reciprocate them toward and from the shell holder, guide pieces carried by the tamping rods, and guides along which said guide pieces slide during longitudinal movement of the rods, said guides being shaped to correspond with the shape of the converging hopper walls and being so located that dur- 120 125 130

- ing the movement of the tamping ends of the rods through the hopper toward the shell-holder, said ends will pass along and close to the hopper walls.
21. In a machine for filling shells, the combination with the shell holder, a hopper and funnels between the hopper and the shell holder, of a series of tamping rods, means to move said rods alternately toward opposite walls of the hopper, means to move said rods toward the shell holder when the rods are moved sideways as stated, guide pieces carried by the tamping rods, guides, on opposite sides of the series of rods, along which said guide pieces slide when the rods are moved longitudinally, said guides being shaped to conform with the shape of the converging hopper and funnel walls and being so located that during the movement of the tamping ends of the rods through the hopper and funnels toward the shell-holder, said ends will pass along and close to the hopper and funnel walls.
22. In a machine for filling shells, the combination with a series of tamping rods, of a shaft, an arm on the shaft, a bell-crank lever, a cam, on one end of the lever, encircling the shaft and having projections adapted to be alternately struck by said arm, a guide, on the other end of the lever, through which said rods extend, means to turn said shaft, and means to reciprocate the tamping rods longitudinally.
23. In a machine for filling shells with explosive powder, a series of tamping rods, means to reciprocate the rods longitudinally and swing them back and forth, a slotted plate through which said rods extend, and a plate carried by each rod and overlapping the slot of the first-named plate.
24. In a machine for filling shells, the combination with a hopper having a longitudinal opening, of a funnel frame extending beneath and secured to the hopper and having formed therein a series of independent funnels communicating with the hopper opening.
25. In a machine for filling shells, the combination with a hopper having a longitudinal opening, of a funnel-frame extending beneath and secured to the hopper and having formed therein a series of independent funnels communicating with the hopper opening, a nipple plate and a series of independent nipples carried thereby communicating with the respective funnels, and means to attach the nipple plate to the funnel plate.

In testimony of which invention, I have hereunto set my hand, at Philadelphia, on this 25th day of September, 1911.
